UNITED STATES PATENT OFFICE.

CHRISTOPH MÜLLESTEIN, OF WEST NEW YORK, NEW JERSEY.

CUSPIDOR.

1,232,957.

Specification of Letters Patent. Patented July 10, 1917.

Application filed October 17, 1916. Serial No 126,110.

To all whom it may concern:

Be it known that I, CHRISTOPH MÜLLESTEIN, a citizen of Switzerland, and a resident of West New York, in the county of 5 Hudson and State of New Jersey, have invented a new and Improved Cuspidor, of which the following is a full, clear, and exact description.

This invention relates to an improved cuspidor and has for an object the provision of an improved arrangement whereby the cuspidor is adapted to be used as a pocket cuspidor.

Another object in view is to form a pocket cuspidor in such a way as to hide the construction when in use while allowing the construction to be such as to produce a substantially air-tight container.

A further object of the invention is to 20 provide a pocket cuspidor in which a pair of gates or shutters is provided and associated with a spring-pressed manually operated member whereby the gates may be loosened and swung to an open position 25 manually when it is desired to use the device and swung to a closed position and tightened or sealed automatically when released.

In the accompanying drawings:

30 Figure 1 is a top plan view of a cuspidor disclosing an embodiment of the invention.

Fig. 2 is a section through Fig. 1 on line 2—2.

Fig. 3 is a section through Fig. 1 on line 35 3—3.

Fig. 4 is an edge view of the cuspidor removed from the covering handkerchief.

Fig. 5 is a sectional view through Fig. 2 on line 5—5.

40 Fig. 6 is a sectional view similar to Fig. 5 but at a slightly lower point, the parts being shown in their open position.

Fig. 7 is a sectional view through Fig. 3 on line 7—7.

45 Fig. 8 is a view similar to Fig. 7 but showing the parts in their open position.

Fig. 9 is an edge view of the casing embodying certain part of the invention.

Fig. 10 is a top plan view of the clamping 50 ring for holding the handkerchief in the casing shown in Fig. 9.

Referring to the accompanying drawings by numerals, 1 indicates a ring which may be termed a casing and which is provided 55 with an annular groove 2 into which part of the handkerchief 3 is pressed by ring 4.

Ring 4 (Fig. 10) is split at 5 and is made of spring material so as to press the handkerchief firmly in the groove 2. In arranging the handkerchief in position a hole is 60 made therein at any point, as for instance, centrally, and the ring 4 inclosed by part of the handkerchief, after which the ring 4 is allowed to grip against the casing 1 in groove 2. The casing 1 is interiorly 65 threaded for receiving a mouth piece 6, the body 7 and the bottom member 8. Body 7 is provided with a beveled or inclined section 9 for directing the spittle to the opening 10 which registers with a passageway or 70 opening 11 in the bottom 8. Journaled in enlargements 12 and 13 of body 7 are pins 14 and 15, respectively. Pin 14 acts as a journal to the outer shutter or gate 16 while pin 15 has an arm 17 rigidly secured at one 75 end and the inner shutter or gate 18 secured thereto at the opposite end and held in place by any means, as for instance, screw 19.

A pin 20 (Fig. 6) extends from the gate 16 and fits into a slot 21 in ring 22, slot 21 80 extending radially so that when ring 22 is moved from the position shown in Fig. 5 to the position shown in Fig. 6, the pin 20 will be moved and, consequently, the gate 16 will be swung to an open position. On the 85 opposite side of the ring 22 to slot 21 is a diagonal slot 23 which accommodates the pin 24 secured to the arm 17. When ring 22 moves from the position shown in Fig. 5 to that shown in Fig. 6 not only will pin 20 be 90 moved and gate 16 moved, but the pin 24 will be moved from near the outer part of the ring to the inner part by reason of the diagonal position of the slot 23. This will swing the arm 17 a short distance and will 95 partially rotate the pin 15 and as said pin is rigidly secured to the gate 18 said gate will be moved from the position shown in Fig. 7 to the position shown in Fig. 8, namely, from a closed to an open position. In this 100 way both gates are simultaneously moved to an open position and when the parts are released they will be moved back to a closed position as hereinafter fully described.

In order to hold the gates perfectly tight 105 and thereby prevent any odor or any spittle from escaping the mouth piece 6 is threaded on to the ring 4 and when the gates are closed this mouth piece is screwed down comparatively tight against the gate 16. In 110 order to open the gates it will be necessary to unscrew somewhat the mouth piece, and

this is done by having the lug 25 rigidly secured to or formed integral with the mouth piece, as shown in Fig. 1. A piston or rod 26 is secured to the lug 25 and extends into the casing 27 where it is acted on by spring 28, said spring and casing being held in place by a stop 28'. The stop 28' is secured to the ring 4 by screws 29 operating in any of the apertures 30 (Fig. 6). It will be observed that a plurality of sets of apertures are provided so as to allow for an adjustment whenever desired.

In order to connect the mouth piece 6 with the ring or plate 22, screws 31 and 32 (Fig. 3) are arranged in the mouth piece and provided with extensions fitting into any of the apertures 33 and 34, respectively. A plurality of apertures are provided in order to make an adjustment in case any of the parts become worn. By the construction and arrangement just described, whenever the lug 25 is pressed by the thumb, lug 28' being held stationary, the mouth piece 6 will be rotated in such a direction as to be unscrewed, and as it rotates it will carry with it the ring 22, which ring through pins hereinafter described, will cause the gates 16 and 18 to swing to an open position, gate 16 swinging through the slot 35 while gate 18 operates in a space between the body 7 and the bottom member 8. It will be observed from Figs. 7 and 8 that the gate 18 is provided with a solid section 36 and an apertured or open section 37, said sections being preferably formed integral with the arm 38 which is rigidly secured to the pin 15.

The bottom 8 is provided with a depending annular sleeve 39 which is threaded interiorly for receiving the stem 40 of the bag 41 or container 41. The bag or container 41 may be made from any suitable material, preferably from a good quality of rubber, and the stem 40 is pressed against the threads of sleeve 39 by a stiff sleeve 42, preferably of metal, which causes the rubber of the stem to fit tightly in the threads and thereby lock the stem to the sleeve, as shown particularly in Fig. 2. The detail construction of the bag 41 may be of any kind without departing from the spirit of the invention, but preferably the bottom part is provided with an outlet member formed with a sleeve 43 clamped in place by a nut 44. The sleeve 43 is internally threaded for receiving a plug 45 for normally closing said sleeve. When it is desired to empty the device this plug may be removed and the gates 16 and 18 opened and water poured into the device so that it will be thoroughly washed and cleaned. It will be noted that when the mouth piece 6 is unscrewed somewhat and the gates are opened by pressing against the lug 25, the spring 28 will be compressed, and when the lug 25 is released, either intentionally or accidentally, the gates will be swung

to a closed position quickly and the mouth piece 6 will be screwed down again so as to produce a reasonably tight joint. In connection with the mouth piece it will be observed that a depending protecting flange 46 is provided which overlaps the ring 22.

What I claim is:

1. In a cuspidor of the character described, a bag or container, a closure therefor comprising a mouth piece, and a spittle guide, a gate arranged at each end of said guide, manually operated means for opening said gates, and automatically actuated means for closing said gates.

2. In a cuspidor of the character described, a bag or container, a closure therefor comprising a bottom member connected to the bag, a ring connected to the bottom member, a body connected to the bottom member and spaced from the ring, a mouth piece spaced from the body, a gate arranged on each side of the body, manually operated means for opening said gates, and a spring for actuating said means for closing said gates.

3. In a cuspidor of the character described, a bag or container, a bottom member, means for clamping said bottom member to said bag or container, a ring connected to said bottom member, a mouth piece rotatably connected with said ring, a pair of gates, means for separating said gates, means connected with said mouth piece for causing said gates to open when the mouth piece is partially rotated, and a spring for causing a reverse movement of the mouth piece for closing said gates.

4. In a cuspidor of the character described, a bag or container, a bottom member connected with said bag or container, a ring connected with said bottom member, a body having a passageway therethrough arranged in said ring, a pair of gates oppositely mounted on said body, said gates being arranged on opposite sides of the body, a mouth piece threaded on said ring, a gate actuating ring connected with said mouth piece, means for connecting said gate actuating ring with the gates so that when the ring is rotated the gates will be opened or closed according to the direction of rotation, and an operating member for rotating said mouth piece whereby when the mouth piece is rotated in one direction the same will be unscrewed and the gates released, while rotation in the opposite direction will cause the gates to be closed and the mouth piece to be tightened thereon.

5. In a cuspidor of the character described, a bag or container, a closure therefor including a pair of gates, a body surrounding said gates, a mouth piece threaded on to said body and clamping one of the gates in position, means for unscrewing said mouth piece, means for connecting the mouth piece with the gates for opening the

gates during the unscrewing action of the mouth piece, and a resilient member for screwing the mouth piece back to its former position and simultaneously closing said 5 gates.

6. In a cuspidor of the character described, a container, a closure therefor comprising a bottom member connected to the container, a casing connected with said bottom member, a body arranged in said casing and spaced from the ends, a gate arranged on each side of said body, said body having an opening therethrough and said gates normally closing said opening, a closure ring, 10 pins connected with said gates and engaging said ring whereby when said ring is rotated the gates will be swung to an open position, a mouth piece connected with said ring and threaded into said casing, a lug for moving 15 said mouth piece whereby when said mouth

piece is moved in one direction the same will be moved away from said gates for loosening the gates, and when moved in the opposite direction for tightening the gates, and a spring acting on said lug for normally 25 holding the mouth piece and gates in a closed position.

7. In a cuspidor of the character described, a container, and a closure therefor comprising a casing, a body arranged in the 30 casing having a passageway therethrough, a gate for closing said passageway, a closure ring acting on said gate for swinging the same to an open and closed position, a mouth piece for actuating said ring, a lug 35 for actuating said mouth piece, and a spring acting on said lug for normally holding the mouth piece in a closed position.

CHRISTOPH MÜLLESTEIN.
